SKIN OPENING MACHINE

William J. Young, Jr., Danbury, Conn.

Application March 27, 1948, Serial No. 17,551

8 Claims. (Cl. 164—60)

1

This invention relates to a skin opening machine.

One of the objects of this invention is to provide a skin opening machine which is simple, thoroughly practical, and durable. Another object of this invention is to provide a machine of the above character which may be manufactured from inexpensive materials at low labor cost. Another object of this invention is to provide a machine of the above character which will be sturdy and well able to withstand continuous hard usage. Another object of this invention is to provide a machine of the above character which may be operated by unskilled labor after a minimum of instruction. Another object of this invention is to provide a machine of the above character which may be easily and safely operated by the user. Another object of this invention is to provide a machine of the above character on which a maximum of skins may be opened in a minimum of time. A further object of this invention is to provide a machine of the above character, the use of which results in substantial savings of fur to the user. A still further object of this invention is to provide a machine of the above character on which skins of all types may be opened. Other objects will be in part obvious and in part pointed out hereinafter.

The invention accordingly consists in the features of construction, combinations of elements and arrangements of parts as will be exemplified in the structure to be hereinafter described, and the scope of the application which will be indicated in the following claims.

Referring now to the drawings in which is shown one of the various possible embodiments of this invention,

Figure 1 is a perspective view taken from a point above the machine;

Figure 2 is a top plan of the machine shown in Figure 1 on a slightly reduced scale;

Figure 3 is a vertical section taken on the line 3—3 of Figure 2;

Figure 4 is a vertical section taken on the line 4—4 of Figure 3;

Figure 5 is a vertical section taken on the line 5—5 of Figure 3;

Figure 6 is a vertical section taken on the line 6—6 of Figure 3;

Figure 7 is a plan view of a "butcher" rabbit skin;

Figure 8 is a diagrammatic view of a cross section of a "sleeve" skin illustrating the effect of

2

the "sleeve" skin opening attachment on a skin at the point it is being cut;

Figure 9 is a bottom plan of the machine; and

Figure 10 is a perspective view taken from a point above the machine in which the "sleeve" skin opening attachment has been removed.

Similar reference characters refer to similar parts throughout the several views of the drawing.

10 As conductive to a clear understanding of certain features of this invention, it might here be pointed out that the machine disclosed hereinafter was primarily developed for opening rabbit skins. As is well known in the art, rabbit skins 15 are harvested in many different parts of the world, and in addition to the variations in sizes between different types of skins, they are removed from the body of the rabbit in different ways. All skins, when delivered to the fur dealer, must 20 be opened so that they will be in a flattened condition. This exposes the fur so that it may be processed and then removed from the skin.

Heretofore, a few skin opening machines have been developed but these have not proven to be

25 practical. This is proven by the fact that in practically 100% of the fur shops, skins are still being opened by skilled labor, using ordinary knives. This method of opening skins is both expensive and inefficient in that it is slow and also

30 a substantial amount of fur is lost. The fur is lost because the knife tears a certain amount of fur from the skin as it cuts, and this fur floats in the air and accumulates on the floor, making an unhealthy condition for labor. Through the

35 use of the machine disclosed hereinafter, the skin opening capacity of labor employed in this capacity is more than doubled and fur loss is practically, if not entirely, eliminated.

Referring now to the drawings, the skin opening

40 machine is mounted upon the top 10 (Figure 1) of a table or bench. The table or bench is constructed so that it is relatively rigid with top 10 a sufficient distance from the floor so that the skin opening machine is readily accessible to the

45 operator. All of the mechanism of the machine with the exception of the motor is mounted upon a plate, generally indicated at 11, which is positioned over an opening 12 (Figure 2) in bench top 10. The front edge 11a of plate 11 slants to the forward edge of the bench, and plate 11 is secured to top 10 by screws 13 (Figures 1 and 2).

The skins are opened by a circular knife 14 (Figures 3, 9 and 10) which is detachably mounted on a shaft 15 by means of nut 16. Shaft 15 extends transversely of the bench top and is

mounted on bearings 17 and 18, which in turn are mounted on supports 19 and 20. Bearings 17 and 18 are combination thrust and radial bearings, and thus prevent movement of shaft 15 transversely of the bench. As knife 14 is securely mounted on shaft 15, the bearings maintain the knife in a set position with respect to the table. Bearing supports are secured to plate 11 by bolts 21 and 22 and screws 23 and 24 (Figures 2 and 9). Shaft 15 has a pulley 25 connected to its free end. Pulley 25, and thus shaft 15, is driven by means of an endless belt 26, which is also connected to the driving pulley of a motor (not shown) mounted on the bench below the skin opening machine. Thus, the motor drives knife 14 through its pulley, belt 26, pulley 25 and shaft 15.

Shaft 15 is so spaced from the under surface of plate 11 (Figure 3) that a substantial portion of knife 14 extends above the upper surface of plate 11. Knife 14 extends through a slot 27 (Figure 9) in plate 11 which has enlarged ends 27a and 27b for purposes to be disclosed more fully hereinafter.

As pointed out hereinabove, rabbit skins are of many different types and all types are turned inside out when they reach the operator. Some skins, such as that illustrated in Figure 7, include pockets A and B which must be cut along lines C and D. Another portion E of this skin is in the form of a sleeve which must be cut on line F. In other types of skins, certain portions of the skins may be pulled inside when the skin is removed from the body, and it is necessary to push these out before cutting. In this machine, which is universal in that it opens all types of skins, the average skin is opened through the use of the skin guide, indicated generally at 30 (Figures 3 and 10). Sleeve skins, which are substantially larger than butcher skins and which are tubular in form, are opened on an attachment, generally indicated at 31, which is mounted on the machine over guide 30. This attachment coacts with guide 30 to guide and support skins as they are fed to the knife.

Guide 30 (Figure 10), which is relatively narrow, tapers to a pointed portion 30a on one end and a rounded nose portion 30b on its other end. A pair of legs 32 and 33 (Figures 3 and 10) are formed on guide 30, extend downwardly from the guide, and terminate in foot portions 32a and 33a which are secured to plate 11 by screws 34 and 35. Legs 32 and 33 form the sole supports for guide 30 and are substantially aligned with the highest point of knife 14 so that they cannot interfere with the operation of the machine. Legs 32 and 33 space the under surface of guide 30 from plate 11, leaving ample space so that a skin can be fed to the knife from either end of the guide 30. Guide 30 is provided with a longitudinal slot 36 (Figure 3) centrally positioned with respect thereto. The upper portion of knife 14 extends into this slot which serves as a shield for the upper portion of the knife and also ensures that the portion of the knife which is doing the cutting will always be angularly positioned with respect to the cut being made.

The nose portion 30b of guide 30 is used for making the cut F (Figure 7), its end entering the skin from the center. The operator draws the skin rearwardly over guide 30, the nose portion 30b (Figure 10) passing through the center of sleeve portion E (Figure 7). As the skin is drawn rearwardly, the body of guide 30 supports the skin, which is pulled upwardly as it is fed rearwardly so that knife 14 makes an even cut

on the line F. Nose portion 30b is also used in turning out any portion of a skin which has been pulled inwardly during skinning by simply pushing the inverted portion of the skin against nose portion 30b. This turns the portion outwardly so that it will be properly cut by the knife. In certain skins, if the type of skin being opened has legs or heads which must be removed, then the skin is turned sidewise to nose portion 30b and the portion to be removed fed to the knife. Ample clearance between guide 30 and plate 11 is provided for this purpose, so that the knife is readily accessible.

In opening corners or pocket portions A and B (Figure 7), the point 30a (Figures 3 and 10) is used. It will be noted that the body of guide 30 slants downwardly at 30c (Figure 3) and that point 30a extends upwardly and rearwardly from the lower portion of the guide 30. The rear end of point 30 is sharp, and its lower surface leads directly to knife 14. This is accomplished by having slot 36 extend downwardly through the forward end of point 30a so that the edge of knife 14 is positioned in the lower end of point 30a. In opening a pocket, point 30a enters the pocket from the inside, and the operator draws the skin outwardly. When point 30a reaches the end of the pocket, it pierces the skin, and then as the forward motion of the skin continues, the unopened portion of the skin slides down the under surface of point 30a to knife 14 where it is cut. Because of the small size of point 30a, pockets of any size may be quickly and easily opened. Thus, on guide 30 any skin may be opened providing the skin is not too large for guide 30 to properly support it as it is being fed to knife 14.

Sleeve skins are too large to be properly cut on guide 30, and accordingly attachment 31 is used. Attachment or guide 31 (Figures 1 and 2) include a body, generally indicated at 40, an arm, generally indicated at 41, pivotally connected thereto and a supporting section 42 connected to body 40. Body 40 is connected to the upper portion of supporting section 42 (Figure 3) so that the under surface of body 40 is spaced from plate 11. Supporting section 42 is secured to plate 11 in any suitable manner, such as by bolts 43 (Figures 1 and 3). Body 40 includes a recess 44 (Figures 1 and 2) within which guide 30 is positioned when attachment 31 is used, and it will be noted that the under surface 45 of the forward portion of guide 30 blends into the under surface of the forward portion of attachment 31. Thus, guide 30 coacts with attachment 31 in supporting a sleeve skin as it is being fed to the knife, and also guide 30, at all times, acts as a shield for knife 14.

To properly stretch sleeve skins as they are being opened, arm 41 is provided. Arm 41 includes a portion 41a (Figures 2 and 3) which extends into a recess 46 cut into attachment 31 beneath the forward portion thereof. Portion 41a, and thus arm 41, is pivotally connected to the body of attachment 31 by means of screw 47. The rear portion of arm 41 has a guiding flange 41b (Figures 2 and 3) which, when arm 41 is in a closed position, fits into a recess 48 in the rear portion of the body of attachment 31. The degree that arm 41 may move outwardly with respect to body 40 is limited by means of a pin 49 (Figures 2 and 5) mounted on flange 41b. Pin 49 extends through a longitudinal slot 50 cut into a plate 51 connected to the under surface of body 40 by screws 52. The outer end of plate 51 is positioned in a recess 53 (Figure 3) so that it does not extend below the lower surface of the

attachment, and thus cannot interfere with the rearward passage of sleeve skins as they are opened.

Arm 41 is at all times biased outwardly by a spring 54 (Figures 2 and 4), one end 54a of which fits in a bore 55 in body 40, and the other end of which is positioned in a recess 56 in arm 41. It will be noted that arm 41 is pivotally connected to body 40 at a point well ahead of the cutting edge knife 14, and that its rear end is positioned a substantial distance behind the same point. Attachment 31 acts very much the same upon a skin during opening as the spreading of the cloth on each side of a seam prior to cutting the threads holding the seam together with a knife. If the cloth is loosely held and an attempt is made to cut the seam, the knife will cut a ragged, wavy line and will not follow the seam. However, if the cloth on each side of a seam is pulled outwardly, then the knife will cut a straight line along the threads.

In opening a sleeve skin which is tubular in shape, the skin is fed onto the forward end of the attachment. When the skin reaches arm 41, arm 41 is moved inwardly, but spring 54 exerts continual pressure upon arm 40 so that the portion of the skin beneath the attachment is spread. For example, referring to Figure 3, the skin 53 is held by the operator along its upper edge K and pulled upwardly so that its general shape in cross section is triangular. As the skin moves rearwardly, the skin is stretched between body 40 and arm 41 (Figure 6), which exert pressure at points M and N (Figure 8). Thus, the skin is stretched tightly at the point it is being cut, and because of this, a straight, even cut is made as the operator moves the skin rearwardly with respect to attachment 31. Because of the length of the attachment, and because it continually increases in width toward its rear end, when the skin is cut the opened portion of the skin is spread for a substantial distance beyond the point at which the cut is made. This places additional tension upon the skin at the point it is being cut, increasing the effectiveness of the cutting action of knife 14.

As pointed out hereinabove, opening skins by hand resulted in a substantial loss of fur. Through the use of the machine disclosed, the amount of loss will be substantially less. However, some fur will be cut from the skin by the knife 14 as it slices through the skins. To save this fur, openings 27a and 27b (Figure 9) are provided in plate 11 at each end of slot 27, and an additional opening 60 (Figure 10) is provided to the rear of knife 14. Opening 60 is partially closed by a downwardly extending portion 61 of plate 11 which shields blade 14. A housing, generally indicated at 62, completely encloses the space beneath knife 14, and this housing leads to a duct (not shown) which empties into a bin. Suction is provided in the duct, and thus all fur cut from the skins is sucked down through openings 27a and 27b into housing 62, and then to the bin where the fur is collected. Opening 60 is provided to ensure the collection of all fur torn from the skins by point 30a as it pierces the skins. Thus, in this machine, the amount of fur removed from a skin during opening is substantially reduced, and all fur cut from the skins is saved.

It will thus be seen that an efficient and practical machine for opening skins has been disclosed. Through the use of this machine, the output of an operator is actually double, and

the job of opening skins is greatly simplified. Furthermore, on this one machine, skins of all types may be opened and manual opening of all portions of skins is entirely eliminated. Accordingly, it will be seen that the several objects hereinabove mentioned, as well as many others, have been successfully accomplished.

As many possible embodiments may be made of the above invention, and as many changes 10 might be made in the embodiment above set forth, it is to be understood that all matter hereinabove set forth or shown in the accompanying drawings is to be interpreted as illustrative and not in a limiting sense.

15 What is claimed is:

1. In a skin opening machine, in combination, a supporting member, a circular knife mounted on said supporting member, means for driving said knife, a guide for the skins being opened, said guide extending longitudinally of the plane in which the blade of said knife lies, the upper portion of said knife extending upwardly through an opening in said supporting member into the body of said guide, and means 20 for supporting said guide so that its lower surface is positioned above the upper surface of said supporting member, said last-mentioned means being positioned directly over the axis of said knife whereby the end portions of said 25 guide are spaced from said supporting member, the leading and rear portions of the cutting edge of said knife between said supporting member and guide being spaced forwardly and rearwardly from said supporting member, said guide having one end which extends a substantial distance from the cutting edge of said wheel and terminates in a substantially blunt end and having another end which is pointed, the under edge of said pointed end leading downwardly to the 30 cutting edge of said knife.

2. In a skin opening machine, in combination, a supporting member, a circular knife mounted on said supporting member, means for driving said knife, a guide for the skins being opened, said guide extending longitudinally of the plane in which the blade of said knife lies, the upper portion of said knife extending upwardly through an opening in said supporting member into the body of said guide, and means 45 for supporting said guide so that its lower surface is positioned above the upper surface of said supporting member, said last-mentioned means being positioned directly over the axis of said knife whereby the end portions of said 50 guide are spaced from said supporting member, the leading and rear portions of the cutting edge of said knife between said supporting member and guide being spaced forwardly and rearwardly from said supporting member, said guide having one end which extends a substantial distance from the cutting edge of said wheel and terminates in a substantially blunt end and having another end which is pointed, the under edge of said pointed end leading downwardly to the 55 cutting edge of said knife.

3. In a skin opening machine, in combination, a supporting member, a circular knife mounted on said supporting member, a guide for skins being opened, said knife extending upwardly past the under surface of said guide, supporting means 60 for supporting said guide so that its lower surface is positioned above the upper surface of said supporting member, said last-mentioned means being positioned directly over the axis of said knife whereby the end portions of said 65 guide are spaced from said supporting member, the leading and rear portions of the cutting edge of said knife between said supporting member and guide being spaced forwardly and rearwardly from said supporting member, said guide being relatively long and narrow and including one portion which extends outwardly a substantial distance from the point at which a skin is cut and terminates in a relatively blunt end, the opposite end of said guide being in the 70 form of a point having substantially the same thickness throughout its length and extending downwardly at an angle toward said knife, the lower surface of said point leading downwardly to the edge of said knife.

3. In a skin opening machine, in combination, a supporting member, a knife mounted on said supporting member, a guide for skins being opened, said knife extending upwardly past the under surface of said guide, supporting means 75 for mounting said guide so that its under surface

is spaced from the upper surface of said supporting member, said guide extending a substantial distance forwardly from the cutting edge of said knife, and means on said guide for stretching the portion of the skin being cut.

4. In a skin opening machine, in combination, a supporting member, a rotary knife mounted on said supporting member, means for driving said knife, a guide for skins being opened, said knife extending upwardly past the under surface of said guide, supporting means for mounting said guide so that its under surface is spaced from the upper surface of said supporting member, said guide extending a substantial distance forwardly from the cutting edge of said knife, an arm pivotally connected to said guide adjacent the outer end thereof, and a spring for resiliently urging movement of said arm outwardly from said guide in a direction directly away from the plane in which the blade of said knife lies whereby the skin being opened is stretched across the lower surface of said guide as it is cut by said knife.

5. In a skin opening machine, in combination, a supporting member, a rotary knife mounted on said supporting member, means for driving said knife, said knife extending upwardly through a slot in said supporting member, a guide, the upper portion of said blade being positioned above the lower surface of said guide, said guide being positioned over and extending longitudinally of the blade of said knife, means supporting said guide so that its lower surface is above the upper surface of said table, said last-mentioned means being positioned rearwardly from the cutting edge of said knife, said guide extending a substantial distance forwardly from the forward end of said knife and gradually increasing in width from its forward to its rear end, an arm pivotally connected to said guide forwardly from the cutting edge of said knife, said arm swinging in a plane transverse to the plane in which the blade of said knife lies, and spring means to resiliently urge said arm outwardly from said guide, whereby said guide and arm coact to stretch the portion of said skin being cut by said knife.

6. In a skin opening machine, in combination, a supporting member, a knife mounted on said supporting member, a guide for skins being opened, said knife extending upwardly past the undersurface of said guide, supporting means for mounting said guide so that the undersurface of the portion of said guide extending forwardly from the center of said knife is spaced from the upper surface of said supporting member, said guide extending a substantial distance forwardly from the cutting edge of said knife, an arm pivotally connected to said guide adjacent the outer end thereof, and means for urging said arm outwardly in a plane parallel to said supporting member whereby the skin being opened is

stretched across the lower surface of said guide as it is cut by said knife.

7. In a skin opening machine, in combination, a supporting member, a rotary knife mounted on said supporting member, means for driving said knife, a wedge-shaped guide for skins being opened, said knife extending upwardly into an opening in said guide, said guide including an entering end positioned forwardly of said knife and an end secured to said supporting member, said guide increasing in width from said entering end at least to the portion of said guide positioned over said knife, said guide extending a substantial distance forwardly from the cutting edge of said knife, an arm pivotally connected to said guide adjacent the entering end thereof, said arm extending longitudinally of said guide at least past rotary knife, and means resiliently urging said arm outwardly from said guide in a direction outwardly from the plane in which the blade of said knife is positioned, whereby the skin being opened is stretched across the lower surface of said guide as it is cut by said knife.

8. In a skin opening machine, in combination, a supporting member, a circular knife mounted on said supporting member, means for driving said knife, a guide for the skins being opened, said guide extending longitudinally of the plane in which the blade of said knife lies, the upper portion of said knife extending upwardly into an opening in said guide, means for supporting said guide positioned over the axis of said rotary knife, the leading and rear edges of said guide being spaced forwardly and rearwardly from said supporting member, one of the ends of said guide being blunt and the other end being pointed and having an under edge which leads downwardly to the cutting edge of said knife, a detachable guide positioned over said first-mentioned guide, said detachable guide being spaced from said supporting member and including an opening in which said first-mentioned guide is positioned, means supporting said second-mentioned guide so that the forward portion thereof is spaced from said table, an arm on said second-mentioned guide pivotally connected to said guide adjacent the forward end thereof, and means resiliently urging said arm outwardly away from said knife.
